UNITED STATES PATENT OFFICE.

DE VER H. WARNER, OF BRIDGEPORT, CONNECTICUT.

DESIGN FOR A CORSET.

SPECIFICATION forming part of Design No. 21,883, dated October 4, 1892.

Application filed April 25, 1892. Serial No. 430,634. Term of patent 7 years.

To all whom it may concern:

Be it known that I, DE VER H. WARNER, a citizen of the United States, residing at Bridgeport, Fairfield county, State of Connecticut, have invented a new Design in Corsets, of which the following is a specification.

My invention relates to a new and original design for corsets, and is illustrated in the accompanying drawing, in which the figure represents one section of the corset embodying my design.

The distinguishing feature of the design consists in the breast-pocket section having upon its upper portion a central vertical section *a*, extending the entire length of the breast-pocket from the upper edge *y* to the lower edge *x* of the corset and having an ornamental lace edging *d*, extending around the top of the breast-pocket section, and two

horizontal bands *c c*, each substantially parallel with the ornamental edge *d*, and between the ornamental lace edging and the band is a series of parallel ribs *e* upon each side of the section *a*, extending in a substantially-parallel direction therewith, the whole constituting an aesthetic and ornamental design applied to the breast-pocket section of a corset.

What I claim is—

The design for a corset, substantially as shown and described.

In testimony whereof I have signed my name to this specification in the presence of two subscribing witnesses.

D. H. WARNER.
